UNITED STATES PATENT OFFICE.

WALTER A. KRENTLER, OF DETROIT, MICHIGAN, ASSIGNOR TO KRENTLER-ARNOLD HINGE LAST COMPANY, OF DETROIT, MICHIGAN, A CORPORATION OF MICHIGAN.

HINGE LAST.

Application filed April 11, 1922. Serial No. 551,507.

To all whom it may concern:

Be it known that I, WALTER A. KRENTLER, a citizen of the United States, and resident of Detroit, in the county of Wayne and State of Michigan, have invented an Improvement in Hinge Lasts, of which the following description, in connection with the accompanying drawings, is a specification, like letters on the drawings representing like parts.

My present invention relates to hinge lasts and more particularly to means for locking the last in extended position, as well as for the purpose of simplifying the construction and rendering lasts of this type more economical and more easily flexed or shortened for removing from the shoe.

In the manufacture of boots and shoes it is important that a last have the forepart and heel part relatively movable for shortening the last to facilitate removal of the shoe as well as for rendering the last capable of ready insertion in a shoe when used as a follower or the like. In the type of hinge last now generally employed, it is of great importance to hold the last parts rigidly, firmly and positively in extended position, as the last is subjected to great pressures during the processes of shoe manufacture at present employed, and therefore the last must be capable of resisting a "breaking" strain or stress while it must still be capable of readily being flexed or "broken" for the purpose of shortening the last and removing it from the shoe without damage to the completed shoe which has been made thereon. In prior hinge lasts of said type, such for example as that shown in my prior Patent No. 1,094,153, issued April 21, 1914, the last construction was illustrated wherein a spring and cooperating locking members were relied upon to hold the last parts in extended position. My present invention is directed more particularly to utilize the very desirable features of the hinge connection and members in a hinge last having said hinge members concealed, protected and supported by the last portions as illustrated in said prior patent, but to eliminate the expense of the spring and cooperating locking devices. An important object is to simplify the construction of such a type of hinge last and yet to provide a positive, strong locking device readily adapted for movement into locking position and also readily removable

when it is desired to flex or break the last. Further I have provided in the present last construction and cooperating locking instrumentalities means which will compensate for wear or looseness and will at all times maintain the last in firm, strong, rigid and positively locked position capable of withstanding the greatest strains and stresses to which an article of this type is subjected. This feature is of special importance, since heretofore locking devices have usually become useless as soon as a slight amount of wear has occurred, or they have necessitated continual adjustments and setting up. My present locking members automatically compensate for wear to any reasonable extent by the simple swinging of the locking devices into engaging position.

A still further feature consists in the arrangement of the cooperating locking parts to constitute an all-metallic bearing, as distinguished from certain prior locking devices which had braces or bearing engagement with the wood of the last. In such former cases the wood quickly became roughened, damaged or indented, and necessarily loosened to a considerable extent and in my present invention I have obviated such a difficulty by having all the locking cooperating members of metal, preferably being a part of the hinge members as explained.

Further features and details of construction will be hereinafter more fully pointed out and claimed.

Referring to the drawings, illustrating a preferred embodiment of my invention,

Fig. 1 is a side view partly in cross-section illustrating my present last in extended and locked position;

Fig. 2 is a view, partly in cross-section, illustrating the last in flexed or broken position;

Fig. 3 is a fragmentary longitudinal view, partly in cross-section, on the line 3-3 of Fig. 1; and

Fig. 4 is a view, partly in cross-section, on the line 4-4 of Fig. 1.

Referring to the drawings, I have illustrated a last having a forepart 1 and heel part 2 with a line of cut dividing these parts of the well-known "knuckle joint" type. In the forepart 1 is bored a circular recess 3 to receive the tube 4 which is secured and braced therein and held by a rivet or pin 5. In the heel part a recess 6 is formed to

receive the heel plate 7, which plate is also pivoted to the wood of the last at 8, and a common pivot 10 unites the two members 4 and 7 and on the center of the knuckle joint. 5 For this purpose the tubular member 4 is slotted at the overlapping portion to afford a bearing for the plate 7 and also for the pivotal pin 10 as clearly shown in Fig. 4. The construction as thus far explained is 10 substantially the same as in my said prior patent and also in my more recent Patent 1,410,477. Thus I am enabled to take advantage of all the important features of the knuckle joint type of hinge, of the tubular bearing 4 and hinge plate 7, each rigidly secured to the respective last parts by pins remote from the line of cut and therefore in the solid wood of the last, while also taking advantage of the present practise in 15 making and assembling hinged lasts of this type.

I form the overlapping portions of the tube 4 and the plate 7 with a pair of cooperating ears or lugs, cutting the wood of the 20 last appropriately therefor, the tube 4 having these lugs at either side of the slot made to receive the plate 7, the same being indicated at 12, the plate 7 having a similar co-operating lug 14, adapted to slide between 25 the pair of ears 12 on the tube 4. When the last is in its extended position, as shown in Fig. 1, the ears 12 and lug 14 are spaced a substantial distance and in this space is fitted a wedge shaped locking lever 30 15, fitted and fastened at 16 to the forepart. This locking lever 15 can be swung into locking position, the wedge shaped portion firmly engaging between the pair of ears 12 on the tube 4, i. e., the forepart hinge member, 35 and against the lug 14 on the plate 7, i. e., the heel part hinge member, which latter is spaced between the ears 12. Thus a firm, metallic, rigid and locking member automatically compensating for any variation 40 in the opening between the lug 14 and ears 12, is provided, interposing a firm metallic device to hold the last extended and affords a lock of suitable strength to withstand any strains to which the last is subjected. In 45

order to unlock the last, the lever 15 is simply slid or moved outwardly at one side as indicated in dotted lines at 18, Fig. 4, and in the position as shown in Fig. 2, and the last is instantly ready to be broken or flexed. This eliminates the expense of installing a spring, greatly facilitating the assembling of the last originally, and also speeding up the unlocking and flexing of the last, as no strength or strain is required to move the last parts against the 50 tension of a spring or other resistant means. 55

This last can be made most economically, with a minimum of parts, comprising only the two hinge members and a third locking device, together with the retaining rivets, 60 pins, etc., and affording a hinge last construction which can be positively, firmly and rigidly locked in lasted position irrespective of the wear or space between the locking lugs and ears on the hinge members, or 65 slight looseness in the pivot and yet which can be instantly unlocked and immediately flexed with a minimum of effort. 70

My invention is further described and defined in the form of claims as follows: 75

A hinge last of the kind described having a tubular hinge member in one part, a plate hinge member in the other part, a knuckle joint for the last members, the said tubular member being slotted to receive the plate hinge member and united by a pivot at the center of the knuckle joint, a pair of locking ears formed on the tubular member and extending laterally outward at one end thereof, a corresponding locking ear formed on the plate hinge member at the end adjacent to the tubular member, and a wedge-shaped locking member pivotally mounted on the forepart of the last for movement in a plane substantially perpendicular to the axis of the tubular hinge member and movable manually into and out of wedging engagement between the locking ears when the last is in extended position. 80 85

In testimony whereof, I have signed my 90 name to this specification. 95

WALTER A. KRENTLER.
